United States Patent Office.

WILLIAM HALLAM, OF CHELTENHAM, MISSOURI.

Letters Patent No. 95,339, dated September 28, 1869.

IMPROVEMENT IN BRICK-KILNS.

The Schedule referred to in these Letters Patent and making part of the same.

To all whom it may concern:

Be it known that I, WILLIAM HALLAM, of Cheltenham, in the county of St. Louis, and State of Missouri, have made certain new and useful Improvements in Brick-Kilns; and I do hereby declare the following to be a full and true description thereof, reference being had to the accompanying drawings, and to the letters of reference marked thereon.

This invention relates principally to the arrangement of flues circumferentially about the bridge-wall of a brick or other kiln, so as to distribute the heat more perfectly; to the construction of the kiln and its flues and bridge-wall, to cause the hot air and gas of combustion to rise up and deflect in the vertical axis of the kiln to its base, and then pass radially to the rising flues in the outer wall, to a space between the crowns, and therefrom to the chimney; and said invention relates, lastly, to the arrangement of steam-escape passages at the base of the kiln, thereby discharging the moisture advantageously.

To enable those herein skilled to make and use my said improvements, I will now more fully describe the same, referring to the accompanying—

Figure 1 as a vertical sectional elevation at line *x y*.

Figure 2 as a sectional elevation at line *x' y'*.

Figure 3 is a sectional plan at line *x'' y''*, showing my said kiln in a form adapted for burning or calcining fire-brick or common brick, tiles, and similar materials.

I use, by preference, a circular form of kiln, although other forms may be used.

Upon a foundation, A, I raise the bridge-wall B and the enclosing wall C to a proper height, say four feet, the external wall receiving the fire-places D.

Above the said height the bridge-wall is built, of dry wall, (loose brick,) in the usual manner, while the walls C' are built as substantially as ordinary brick-and-mortar walls generally are made, and usually with a fire-brick inner lining, and are arranged with doors or openings for inserting the green brick in the kiln.

Upon the walls C' are the crowns E and E', forming an intermediate passage, E'', which communicates with the chimney, or smoke-stack F. The crowns E and E' are provided with loop-holes e, to enable the fireman to inspect the interior while burning the brick in the usual manner.

The fire-places D are arranged in the usual manner for burning wood or coal, but in order to cause a more perfect combustion in the after chamber D' of the fire-places, I arrange side flues d, in the wall C, which are placed between the fire-places, and run radially back to a proper distance in the wall, and then are carried about on a circular line to the fire-chamber, as shown

in fig. 3. Said flues have suitable dampers to regulate the air flow.

To distribute the heated gases as they pass out of the chamber D', the bridge-wall B has the flues b, thus causing said gases to pass to all points on the circumference of the bridge-wall.

This part of the bridge-wall, in which are the said distributing-flues, will be built of good brick masonry, laid in mortar, to give the same the proper permanency.

The green brick are piled in the usual manner, to extend the bridge up higher, and the said brick are piled within the kiln otherwise as usual.

The products of combustion pass up outside of the bridge-wall in the annular space between the same and the enclosing walls C C', and then, under the inner crown E', move toward the centre of the kiln. Said gases then pass down to the base of the kiln, to enter the radial flues G, which carry the same to the ascending flues H, built in the walls C C'.

By means of said flues, the gases reach the space E'', between the crowns, and here again there is usually a second or final combustion of such gases as have escaped the complete oxidation in the furnaces and lower flues and passages.

The chamber E'', therefore, acts as a top heater, while the vertical flues leading thereto act as side enclosures, to case the inner kiln in a heated-gas envelopment. The gases finally escape at the chimney F.

Dampers are arranged in the several flues and at the chimney, to regulate and control the heat, and to preserve the same in the usual manner.

In order to lead off the moist air and steam escaping from the green brick as readily as possible, and to prevent the same from rising in the kiln, to cause damage and inconvenience, I arrange the steam flues I between the fire-places, and running radially to the inside of the bridge-wall, about on a line with the top of the foundation A.

My said kiln is fired and charged with brick in the usual manner, but by the action of the improved arrangement and construction of the parts herein-before described, the calcined brick thus made is thoroughly burned, and presents true "unwarped" edges, while the operation of burning with said kiln is in a high degree economical and certain of result, even with material requiring the highest heats, such as fire-clay.

Having thus fully described my invention,

What I claim, is—

1. The bridge-wall B, arranged with distributing-flues b, and combined with the furnaces D D', substantially as set forth.

2. The arrangement of flues, furnaces, and bridge-

wall in such manner that the heated gases shall rise in the annular chamber, without the bridge-wall, then pass down the centre of the kiln to the base thereof, to be carried to the circumference, and rise to the chamber between the double crown, and from there pass to the chimney, substantially as described.

3. The steam-passages I, arranged at the base of the kiln, substantially as and for the purposes set forth.

WILLIAM HALLAM.
